UNITED STATES PATENT OFFICE

2,545,361

AUTOMATIC PHONOGRAPH

Anthony M. Kasnowich, Grand Rapids, Mich., assignor to Automatic Instrument Company, Chicago, Ill., a corporation of Michigan

Application May 10, 1946, Serial No. 668,682

1 Claim. (Cl. 274—10)

1

This invention relates to improvements in automatic phonographs, and one of the main objects of the invention is to provide a simplified mechanism which is positively interconnected for perfect coordination between concurrently and consecutively related moving parts, so that the functioning of various elements is inherently in correctly timed relation to the functioning of the other elements.

Such machines are very frequently installed in public places, and therefore subjected to misuse as well as to a great deal of deliberate abuse. Accordingly, further objects of the invention are to provide a construction which is not likely to get out of order, which does not require frequent and accurate adjustment and servicing, and in which replacements which might become necessary are easily made.

The automatic record changer disclosed herein is similar in its broad general aspects to that disclosed in United States Patent No. Re. 21,514, to C. H. Green, reissued July 23, 1940. It radically departs from the Green structure primarily in a simplification of the arrangement for effecting reversal of the record transfer mechanism. A long standing problem in the automatic record changer art, particularly in the phase thereof that relates to automatic phonographs capable of playing either side of a record disc, arises from the complicated mechanisms heretofore employed for that purpose and their attendant operating difficulties. The Green structure includes a control shaft and a complex assembly of gears and clutches for causing the shaft to rotate in one direction when the record disc is taken from the magazine and placed on the playing turntable, and in another direction when the record disc is returned, following play, from the turntable to the record magazine. It is a primary object of my invention to provide a more effective and simple structure for performing these functions. In accordance with my invention, I employ a control shaft which always moves in one direction, and a simple mechanical-motion train coupling that shaft to the transfer mechanism in such a manner as to drive the transfer mechanism in either direction, as the operating cycle requires, and as is clearly shown in the following description. The structure which I provide represents a relatively simple solution to this long standing problem and a significant advance in the elimination of operating difficulties and excessive manufacturing costs.

The construction disclosed in the above mentioned Green reissue patent may be understood

2

to be substantially the same as that of the automatic record changer herein disclosed in respects other than those specifically pointed out herein; and that patent is incorporated by reference herein for the purpose of showing what is conventional in this art.

Other objects and advantages will become apparent in the following description, taken with reference to the accompanying drawings, in which an illustrative embodiment of the invention is shown.

Fig. 1 is a plan view of the automatic phonograph mechanism of this invention.

Fig. 2 is a vertical longitudinal section taken substantially on the line 2—2 of Fig. 1.

Fig. 3 is a partial elevation, looking from the rear, or opposite side, with parts broken away.

Fig. 4 is an enlarged fragmental plan view, with parts omitted and parts broken away.

Fig. 5 is a transverse section taken on the line 5—5 of Fig. 4.

Fig. 6 is a transverse section taken on the line 6—6 of Fig. 4 looking toward the turntable.

Fig. 7 is a vertical section of the mechanism taken on the line 7—7 of Fig. 4.

Fig. 8 is a horizontal section taken on the line 8—8 of Fig. 7.

Fig. 9 is a view of the magazine, taken on the line 9—9 of Fig. 1.

Fig. 10 is an elevational view of the machine, looking from the right of Fig. 1.

Fig. 11 is a detail view on an enlarged scale of part of Fig. 5.

Fig. 12 is a plan view of certain clutch operating means shown in Fig. 4.

Fig. 13 is a perspective view of operating means of Fig. 12.

Fig. 14 is a face view of cam means for actuating the means of Figs. 12 and 13.

Fig. 15 is a view of a detail looking from the right of Fig. 9.

Fig. 16 is an end view of a track member shown in Fig. 9.

Fig. 17 is a view of a cam member for controlling the operation of the record gripping members.

Fig. 18 is an elevational view of one of the clutches employed in the present machine.

Fig. 19 is a plan view of a detail shown in Fig. 11, and

Fig. 20 is a view, on an enlarged scale, of the driven pulley and its overload clutch shown in Fig. 3.

The mechanism to be hereinafter described is

mounted on or carried by a skeletonized cast base 10.

The record discs 12 (see Figs. 1, 2 and 9) are placed edgewise in evenly spaced vertical pockets or slots provided between vertically disposed plates 14 which are provided with integrally formed ears 16 at their lower ends. The plates 14 are spaced apart by metal spacers 18, between each pair of which is disposed a spacer 20, preferably of fiber, thus providing between each pair of adjacent plates, a slot to hold a record disc 12.

The inner side of the magazine is carried by and free to slide forwardly and rearwardly of the machine on a rod 22 which passes freely through a sleeve 24 which secures the assembly of plates 14 and spacers 18 and 20 at said inner side firmly together by means of nuts 26, the ends of said rod 22 being secured to lugs 28 up-standing from the base 10.

Through the ears 16, and spacers 18 and 20 at the outer side of the magazine assembly, is also passed a rod 30, provided at each end with a nut 32 in order to hold the assembly securely together at this its outer side.

Supported by lugs 34 depending downwardly from the magazine assembly is a triangularly-shaped carriage 36 (see Fig. 1), pivoted on the apex of which is a roller 38 which is guided by and can roll along a track formed by spaced apart flanges 40 inturned from an upstanding member 42 secured to the base 10. The magazine is thus supported for free movement, at its outer side, on the carriage through the track member 42 and roller 38, whilst at its inner side, it is supported by and free to slide on the rod 22 as above explained. Thus the magazine is free to be moved in one direction or the other to bring a selected disc into position, as will be described hereinafter.

The magazine is driven by a shaft 44 (see Fig. 2), the left end of which has a pinion 46 formed thereon which meshes with an endless rack 48 fixedly secured to the underside of the carriage 36. The shaft 44 is guided for vertical movement (see Fig. 6) in a slot 50 in a plate 52, secured as by screws 54 near the bases of bearing posts or standards 56 and 58, and is driven from its right-hand end as will be described later.

On the base, adjacent the rear right-hand corner thereof as viewed in Fig. 1, is mounted a driving motor 60 adapted to be operated from any usual source of electric power. In front of the motor 60 is provided a standard 62 which carries the usual turntable 64 which is adapted to be rotated from the shaft 61 of the motor 60 through a connection 66 and a worm 68 which drives a gear wheel 70 secured to the turntable shaft 12.

To the opposite end of the motor shaft 61 is secured a pulley 74 which drives, through a belt 76 and pulley 71, a control shaft comprising three sections 78, 80, 82, which are adapted to be interconnected or disconnected by clutches 84 and 86 to control certain operations of the mechanism as will hereinafter be explained; the pulley, it will be noted, being fixed to the shaft section 78.

It will be noted, being fixed to the shaft section 78, To shaft section 80 is secured a worm wheel 88 (see Figs. 4 and 5) which meshes with a pinion 90 secured to one end of a counter drive shaft 92 which is normal to the control shaft section 80. The shaft 92 is also provided with a clutch 94, the purpose of which will be explained later on herein. The drive shaft 92 is carried by and free to rotate in lugs 96 (see Fig. 6) up-

standing from the base of the machine, and adjacent the end opposite to that which carries the pinion 90 has secured thereto a worm 98 which engages a gear wheel 100 secured to a transfer shaft 102 disposed at right angles to the counter-shaft 92 and which transfer shaft drives the record transfer mechanism and operates the pick-up mechanism and is rotatably mounted in the bearing posts or pedestals 56, 58 and in an outer post 104 (see Fig. 6).

The construction of the record transfer mechanism will now be described, with reference more particularly to Figs. 4 to 8.

In alignment with, and above the shaft 102 and between the bearing pedestals 56 and 58 is rotatably mounted a barrel 125, shown in section in Figs. 7 and 8, which has an axial bore 126 extending through its pintles 127 and 128, and has a transverse bore 129 in the portion between the bearings.

In the transverse bore 129 are slidably mounted gripper support members comprising a sleeve 130 and the stem 131 of a button or disc member 132. The sleeve 130 is formed integral with 25 a rectangular, outer finger supporting block 133 which is guided between the cheeks of the bearing pedestals 56 and 58 to support the arm 134 upright in the normal position of the transfer, the arm 134 being fixedly secured to the block 30 133. The cheeks of the bearings are cut away to allow the block 133 to rotate in the forward positions of the transfer in which the arm is ro-

35. A small rod 136a extends centrally through the sleeve 130 and rigidly connects the button member 132 to an arcuate grooved inner record gripping block 136. A sleeve 137, pinned to the rod 136a and gripper block 136, is provided, which extends slidably into the bore of the sleeve 130 and is splined thereto by a key 138, seated in the sleeve 137, for preventing relative rotation between the inner gripper 136 and the outer gripper 139, which is fixedly mounted on the outer end of the arm 124, Fig. 2.

45 outer end of the arm 134, Fig. 2.
Normally the outer gripper is supported by a bar 139a rising from the base 10; and in playing position the gripper 139 rests on an upstanding bar 139b which is bolted to the opposite end of 50 the base at the right of the turntable.

50 the base at the right of the turntable.
The gripper blocks 139 and 136 are drawn together to grip a record disc by a spring 140 which is compressed between the inner end of the sleeve 137 and the bottom of the bore in the
55 sleeve 130; and normally the grippers are separated by means of a wedge plunger 141. The plunger is slidably disposed in the axial bore 126 and has a bifurcated and reduced end portion 142 which embraces the rod 136a and extends between the inner ends of the sleeve 130 and the
60 stem 131, so that, when the plunger 141 is forced inwardly, the wedging surfaces 143 separate said inner ends and open the grippers to release the record.

65 In Fig. 7 the above parts are shown in normal condition, with the gripper open; and in Fig. 8, the plunger 141 has been withdrawn to allow the gripper to close, under the action of the spring 140, and engage the periphery of a record disc.

70 The arcuate arm 134, Fig. 2, is parallel with and partially encircles the discs in the magazine. This permits close spacing of the discs; and the grooved gripper blocks are in the form of segmental arcs, so that very little pressure is required across the discs to hold them very securely.

As clearly shown in Figs. 1, 4, 5 and 6, the transfer drive shaft 102 has, fixedly secured thereto, a face cam 145 for the operation of the plunger 141 to close the grippers to pick up a record to transfer it to the turntable or from the turntable to return the record to the magazine after it has been played and to open the grippers when the transfer is at rest with the arm 134, either over the magazine or in the forward position encircling the turntable.

This is accomplished by means of a bell crank lever 146 which is pivotally mounted in a bracket 147, secured to the pedestal 56. The lever 146 has a bifurcated end 148 which engages in a groove 149 provided in the outer end of the plunger 141, and has a ball portion 150 which is engaged in a groove 151 (see Fig. 17) in the cam 145. Normally the ball 150 is in a radially remote portion of the cam groove with the plunger in and the grippers separated, but when the grippers are to be closed, the ball is moved into a portion of the cam groove which is closer to the axis of the shaft 102. This rotates the bell crank 146 clockwise and withdraws the plunger 141, permitting the disc to be gripped until the record is deposited on the turntable, whereupon the ball 150 travels back to the remote portion of the cam groove and reopens the grippers to release the disc.

In the reverse movement in which the disc is lifted from the turntable and returned to the magazine, the plunger operation is automatically reversed to grip the disc before it is lifted, and to release the disc when it is back in position in the magazine.

The transfer barrel 125 is rotated, after the grippers are closed, by means of a quadrant gear 152, Fig. 2, pivoted at 152c and this quadrant gear meshes with a gear wheel 153 fixed to the outer end of the barrel pintle 128. The quadrant gear 152 is in turn actuated by a pin 152a projecting from a disc 82a secured to the inner end of shaft 102, said pin working in a slot 152b in the quadrant gear, the contour of the slot being such that the quadrant is moved in one direction when a disc is to be deposited on the turntable, and in the reverse direction when the disc is to be returned to the magazine, to move the barrel 125 accordingly.

During the turning movement of the barrel and transfer parts, and while the block 133 is out of engagement with the cheeks of the bearing pedestals 56 and 58, the button 132 is eccentrically engaged by one or the other of a pair of selectively projected plungers 154 and 155 (see Fig. 6), slidably mounted in a plate 156 fixedly secured to said pedestals, to turn the gripped record disc into the horizontal plane of the turntable, or back into the vertical position for reinsertion in the pockets of the magazine after playing.

The spherical face of the button 132 is provided with angular grooves 157 and 158 which extend parallel to an axial line between them and inward from the margin, and then at right angles again outwardly, Figs. 5 or 6. Then as the button swings past the plungers in the forward movement of the transfer, the projecting plunger enters one side of its groove, strikes the angle and rotates the button and transfer arm, laterally ninety degrees, and then passes out the other tangential portion of the groove. During the return movement, the plunger passes through the groove in the opposite direction and turns the arm back to the vertical position.

The plungers 154 and 155 are slidably supported, Fig. 6, in the upturned end portion 159 of the plate 156, and the lower ends of the plungers are pivotally connected to opposite sides of a rocker plate 160, which is centrally pivoted to the supporting plate 156. The lower edge of the rocker plate 160 is centrally recessed to accommodate the angular end of an operating lever 161, medially pivoted on the plate 156, below the rocker plate, and said angular upper end is formed so that the rocker plate is locked in either position in which it is moved by moving the lower end of the lever 161.

The operative position of the plungers 154 or 155 with relation to the barrel 125 is controlled through the lever 161, by a lever 162, pivoted at 163 to the plate 52, and having an angularly-position slot 162a through which is freely passed, as well as through the slot 50, the shaft 44 carrying the pinion 46 which moves the magazine through the rack 48. The position of the pinion 46 in the track controls which side of a record will be played; if it is in the lower half of the track one side of the record will be played; if in the upper half, the opposite side of the record will be played. Hence, as the position of the shaft 44 in the slot 162a is varied, the lever 162 will be rocked accordingly to place one or the other of the plungers 154 or 155 in operative position to rotate the barrel in one direction or the other to place the selected side of the record upwards on the turntable.

A pick-up comprising a long arm 41 having a stylus 43 (see Figs. 1 to 3) is pivotally mounted on a shaft 45 which projects upwardly from a post 41 provided on the rear side of the base 10.

The pick-up arm is also permanently connected for operation to the shaft 102 so that its movements are positively coordinated with the movements of the transfer to swing the arm over and lower it onto the outer portion of the record when a disc is placed on the turntable, and to raise and swing the arm away from the turntable before the disc is removed.

The base 166 of the pick-up arm 41 has a forwardly projecting arm portion 167, Fig. 3, which rides on the flange 168 of a cam 169 which is fixedly mounted on the rear portion of the shaft 102, particularly shown in Figs. 3 and 4. The flange 168 normally lifts the stylus clear of the turntable, but has a flattened portion 170, Fig. 3, which lowers the arm and the arm is swung over the table by means of a downwardly projecting pin 171, secured in the arm 167, which pin is engaged in a groove 172 formed in the periphery of the cam 169.

The groove has a circumferential portion near the outer end of the cam for holding the stylus in normal position away from the turntable, as best shown in Fig. 4. The groove then extends helically on the surface of the cam to swing the arm over the table, then has a portion 173, which leaves the pin free to move as the stylus moves toward the center of the disc in playing a record, and then has a portion to swing the stylus back out from over the turntable after it has first been lifted again by the cam 169.

The selecting operations are controlled as follows:

Extending across the machine is a selector mechanism frame comprising spaced vertical end plates 101 and 103 between which is rotatably supported a horizontally disposed selector drum 105 having a shaft 107, the ends of which project through said plates and thus support the drum.

The selector drum is driven by an encompassing gear wheel 193 secured thereto approximately midway its length from a worm 195 (see Figs. 5 and 11) formed on the end of the shaft 82.

The surface of the drum is provided with a helically arranged row of regularly spaced projecting selector lugs 174, extending the length of the drum.

Between the selector frame plates 101 and 103 are fixedly mounted a selector lever support bar 176, Fig. 5 or 11, a slotted selector latch support bar or frame 177; and a selector lever spacing comb 178, in which is suitably supported a series of selector units corresponding to the twenty sides of the ten discs.

Each selector unit comprises: a selector lever 179 which projects through a corresponding slot in the comb 178, and has its lower end pivotally mounted on the bar 176 through a slot 176a; a depending latch lever 181, and a solenoid 182, the solenoids being arranged in two rows to save space laterally.

The selector levers 179 have projecting arm portions 183 for engagement in notches 184 provided in the latches 181; and the corresponding levers and latches are connected by springs 185 and 181a to the frame 177, so that, in normal position, as shown in Fig. 5, the selector levers are locked away from the drum and out of engaging relation with their corresponding lugs 174.

When a solenoid is energized, the corresponding latch 181 is attracted and disengaged from its associated lever 179, with the result that the upper end of the latter is swung inwardly towards the drum by the pull of the spring 185 on the arm 183, and into the path of the corresponding lug 174. As the drum is rotated, the lug 174 contacts with an angular projection 187 on the upper portion of the lever, and forces the lever downwardly and continues to do so, force it downwardly until the lug slips off the inner end of the projection 187. When this occurs, the solenoid has been deenergized and has allowed the latch 181 to be pulled, by the spring 181a, into contact with the lever 179 so that the projecting arm 183 enters the notch 184 and strikes the upper end of the notch when the lever is free from the lug and pulled upwardly again by the spring 185. This restores the selector parts to the normal locked position.

Rotatably mounted in and extending between the frame plates is provided a clutch operating shaft 188. This shaft is provided with a lateral vane 189a, so that when a lever 179 is pressed downwardly by its lug 174, the vane 189a of the shaft 188 is contacted by the lower end 183 of the lever, and the shaft 188 is rotated clockwise for a purpose which will hereinafter be explained.

On the outer face of the frame plate 103 is mounted the starting switch 191 which is closed, as will be hereinafter described, on the operation of a selector lever and the insertion of a coin in the coin chute (not shown), and the machine will immediately start to function.

It should here be explained that at the end of the preceding operation the transfer mechanism and the stylus operating means were rendered inoperative by the declutching of the shaft 82, which, in turn, rendered the shaft 102 inoperative, the shafts 78, 80 and 82, on the other hand, being left operative, the clutches 84 and 86 between them being left in their clutching positions.

To return to the present operation, the magazine will move, its operating shaft 44 being

rotated by a pinion 200 (Fig. 5) from a worm 202 on the shaft 82 until the lug 174 of the selected record meets and depresses the corresponding selector lever 179. This depression of the lever 179 will rotate, as hereinbefore stated, the clutch operating shaft 189, which, through a pin 204, which works in a slot 205 in one end of a shifter rod 206, will retract the rod to open the clutch 86 to stop rotation of the shaft 82 and the movement of the magazine, the latter having now reached the position where the selected record is in position to be gripped by the grippers 136 and 139.

The clutches 86 and 94 are respectively operated by pins 208, 210 which project horizontally from a vertical rotatable turret 212 which is pulled in one direction by a spring 214. Thus, in the operation above described, the shifter rod 206 will rotate the turret against the action of the spring 214, and at the same time will move the pin 210 to clutch in the shaft 92 and hence the shaft 102 and the transfer and stylus mechanisms operated thereby, both of which mechanisms will now obviously start to operate, of course in proper sequence, to perform their respective functions, which will be clear from the description hereinbefore appearing.

In the rotation of the transfer shaft 102, the stylus arm pin 171 is first in the circumferential portion of the groove in the cam 169 which is fixedly mounted on the shaft 102. When the disc is placed on the table, the helical portion of the groove engages the pin and the arm is swung over the edge of the disc and lowered, by the flat surface 170 of the cam flange 168 moving into cooperative relation with the stylus base projection 167.

This movement of the stylus of course occurs during the period in which the gripper is being opened; and when the stylus is lowered the pin 171 is free to travel in the widened portion 173 of the cam groove.

At this point, that is to say, the placing of the needle 43 in playing position, all of the mechanism is disconnected by operation of the clutch 84, leaving only the pulley 77 and its shaft 78, and, of course, the motor 60 and the turntable rotating. The opening of the clutch 84 is brought about by a horizontally disposed pin 216 carried by a vertical pivot 218 to which is connected one end of a shifter rod 220, the other end of which has a spring 222 secured thereto, and to which rod is also attached the lower bent-over end of a leg 223 (see Fig. 13) depending from a horizontally disposed disc-like member 224, the latter also having a projection 226 to the outer end of which is secured a spring 228, the opposite end of which is secured to a like projection 230 on another disc-like member 232 superimposed on the member 224, both of said members being rotatably supported on a pillar 234 fixed to the base 10. The member 224 also carries tangentially thereto a roller 236 which has rolling contact with a circular track 238 (see Fig. 14) provided in the cam 169. The track, however, has an inwardly facing hump 240, and when the roller 236 strikes this in the rotation of the cam the result is that through relative movement between the members 232, 224 brought about by the spring 228, via the leg 223, the shifter rod 220 is thrown to the right and the clutch opened at the time and for the purpose above indicated.

After the record has been played, the clutch 84 has to be restored to operative position so that

the disc can be transferred back to the magazine.

Fixedly secured in front of the downwardly depending portion 167a of the arm 167 is an arcuate guide 242 in which is adapted to move freely a slide 244 having upturned ends 244a and 244b which are located in the path of the side edges of the apron 167a of the arm 167. Thus, as the arm is moved outwardly, the apron will push the slide outwardly through contact with the end 244b. On the other hand, as the arm moves inwardly as the stylus moves inwardly along the grooves of the disc the apron 167a will move the slide inwardly by contact with the end 244a. This inward movement will continue until the playing of the disc is completed whereupon the end 244a will strike the upper part of a bent rocking lever 246 pivoted on the disc member 232, tip it inwardly to release its depending portion 246a from a notch in the disc 224, thus releasing the leg 223 and allowing the spring 222 to pull the shifter rod inwardly to move the pin 216 to restore the clutch. As the stylus arm is returned to its non-playing position, the slide is, of course, moved back to its outward position by the apron 167a.

After the record has been returned to the magazine, the shafts 92 and 102 must be returned to their inoperative conditions and the shaft 82 restored to its operative condition, ready for the next operation of the machine, and these steps are effected simultaneously through the turret 212 which, it will be recollect, towards the commencement of operations, was rotated clockwise against the tension of the spring 214 and during subsequent operations the turret has been maintained or locked in this position by a latch bar 250 (see Fig. 4) pivoted in a bracket 252 secured to the base 10 and adapted at its front end to engage a stop 254 on the base of the turret. The rear end of the latch bar 250 has an upstanding projection 256 (see Fig. 6) which at the end of the cycle of operations is overridden by a pin 258 projecting from the cam 145. This contacting of the said parts tips the latch bar out of contact with the stop 254, thus permitting the spring 214 to rotate the turret anticlockwise and restore the mechanisms under its control to their original positions.

This accomplished, the machine must be shut down, and this is brought about by a projection 260 on the disc 82a (see particularly Figs. 2, 4 and 6) which depresses a lever 262 pivoted at one end to a bracket 263 on the base 10, the other end of said lever in turn being connected to and hence depressing one end of a bent lever 264 pivoted at 266 to the selector end frame 103, this depressing action being against the pull of a tension spring 268. To the opposite end of the lever 264 is pivoted a vertical lever 270, also under the influence of a tension spring 272.

The upper end of the lever 270 works in a horizontally disposed slot formed in a plate 274 secured to the frame member 103, said lever having a notch 270' which, under certain conditions, is adapted to engage the arm 191' of the switch 191.

Pivoted between the end frames 101 and 103 is a rocking lever 276 having a depending portion 276' which extends across the machine in front of the upper ends of the row of selector levers 179 (see Fig. 11). On the lever 276, outside of the end frame 103 (see Fig. 6), is fixed a cam 278.

Now when a selector lever 179 is moved forward on operation of the machine by a user, the depending portion 276' of lever 276 is forced for-

wardly, thus rotating the cam 278 to push the lever 270 to the left (Fig. 6) to free the switch arm 191' from the notch 270' allowing it to drop to close the switch and start the machine in operation.

By the time the record magazine has been moved, in the operation of the machine, to place the selected record in position to be transferred to the turntable 64, the disc 82a will have been rotated to such position as to move the projection 260 from the high part of the lever 262 (see Fig. 2). This will allow the inner end of the lever 264 to move upwardly under the influence of the spring 268 and the outer end thereof to drop, pulling down with it the lever 270, the spring 272 at the same time pulling the upper portion of lever 270 outwardly. Hence, when the lever 270 is again raised at the end of the cycle of operations, the notch 270' will be in position to engage the switch arm 191', raise it, and thus open the switch to shut off the machine.

However, if a further record has been selected for playing prior to the completion of the playing of a first record, the switch will not be opened on the completion of said first record-playing operation because, in such case, the cam 278 will hold the lever 270 vertical and hence when said lever is moved upwardly at the end of the playing cycle, the notch 270' will miss the switch arm 191' and the machine will continue in operation to play the former record selected.

In Fig. 20 is shown means for preventing damage to the machine in the event that some part thereof jams. To this end the driven pulley 77 is provided with an overload clutch comprising a latch member 302 pivoted at 304 to the pulley and having a tapered key 306 which normally projects into a correspondingly-shaped keyway 308 cut in the shaft section 78, thus locking the pulley and shaft section together for rotation. In a slot 310 cut tangentially in the pulley is mounted a headed pin 312, the head of which is pressed by means of a spring 314 into engagement with the inner end of the latch member 302. The pressure of the spring 314 is adjustable by a screw 316 threadedly engaging the correspondingly threaded interior of the slot 310. As will be understood, when the load exceeds the pressure of the spring, the key will be forced from the slot 308 and the connection between pulley and shaft section broken. After proper adjustment or repair has been made to the machine, the overload clutch can be manually reset.

It is to be understood that various modifications may be introduced into the structure hereinbefore described without departing from the spirit and scope of the invention as defined in the appended claim. As one example of such modification, I may cite the fact that instead of employing but one motor to perform all of the necessary operations of the machine, I may utilize a separate motor to effect the required rotation of the turntable.

I claim:

65 In an automatic phonograph, a magazine for storing a plurality of records, means for selecting a particular record to be played, a turntable, means for transferring said selected record from said magazine to said turntable and back again to said magazine from said turntable, after the record has been played, means for moving said magazine for placing said record in position to be so transferred, a pick-up arm and stylus carried thereby adapted to be placed in position to play 70 said selected record when placed upon the turn-

table, a source of power, a control shaft rotated in one direction only by said source of power, said control shaft comprising three sections, a clutch between the first and second sections of said shaft and a second clutch between the second and third sections of said shaft, a shaft for positioning the magazine to permit a selected record to be transferred to the turntable, driven from said third shaft section, a drive shaft driven from said second control shaft section, a third clutch in said drive shaft, a transfer shaft driven from said drive shaft for controlling the operations of transferring the selected record from the magazine to the turntable and back again to the magazine and for placing said pick-up arm in position to play said record, and for returning the pick-up arm and stylus to an inoperative position on completion of the playing of said record, and means under control of said pick-up

arm for operating the clutch between said first and second control shaft sections.

ANTHONY M. KASNOWICH.
